(57) **CLAIM**

The ornamental design for a surveillance camera, as shown and described.

DESCRIPTION

FIG. 1 is a front view of a surveillance camera showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a front perspective view thereof.

The even broken lines in the views show portions of the surveillance camera that form no part of the claimed design. The boundary lines shown in dot-dash form designate bounds of the claimed design. It is understood that the claimed design extends to the boundary but does not include the boundary.
